UNITED STATES PATENT OFFICE
Alfred C. Schoepfer, St. Petersburg, Fla.
Application November 2, 1948, Serial No. 57,904
4 Claims. (Cl. 20—40)

1
This invention relates to means for preventing breakage of window glass, especially large plate glass, by pressure above or below normal atmospheric pressure on the exterior surface thereof by wind, the object being to provide a comparatively simple and inexpensive structure particularly adapted for use for large store windows liable to breakage by wind pressure or a reduction in pressure below normal.

These and other objects and features of the invention are hereinafter more fully described and claimed and apparatus embodying my invention is shown in the accompanying drawing in which—

Fig. 1 is an elevation showing my improved window brace in association with a glass supported thereby with the suction cups shown partly in section.

Fig. 2 is a section on line 2—2 of Fig. 1.

Fig. 3 is a section taken on line 3—3 of Fig. 1.

Fig. 4 is a side elevation of an alternative form of the window supporting element with the suction cups shown partly in section.

Fig. 5 is a plan view of a spanner taken on line 5—5 of Fig. 4.

Fig. 6 is a section taken on line 6—6 of Fig. 4.

As shown in Fig. 1 the device is positioned between the opposite sides 1 and 2 of an opening in a building. The opening on each side has a frame 32 and 33 to receive a glass 5 and in contact with the inner face of the glass are two rubber cups 6 and 7 having the periphery 8 and 9 in contact with the glass. The base 10 of the cup has a threaded screw 11 and the head 12 is positioned within the body of the rubber cup as shown in Fig. 1.

There may be one or several such cups depending upon the size of the window glass and in each case there is a turnbuckle 13 in one end of which the screw 11 is threaded and the other end of which is threaded to receive the screw 14 having a threaded tubular element 15 thereon.

On the side 1 of the window opening is secured a plate 16 and on the opposite side of the opening is a similar plate 17. Each of the plates 16 and 17 has a bar 18 formed within the inturned edges 19 thereof and the plate 16 is secured to the upper wall 1 by means of screws 20. The edge 19 of each plate has an aperture 21 to receive the end 22 of a hook 23 and on the terminal inturned end 24 of the hook is a tubular element 25 shown more particularly in Fig. 2.

The upper and lower tubular elements 24 and 25 are of a U-form and a cable 26 engages within the upper and lower tubular elements. The cable

2
has at each end thereof a hook element 27 and 28 which respectively engage in the eyed elements 29 and 30 of the turnbuckle 31. These elements 29 and 30 are threaded in the respective ends of the turnbuckle 31 which is here shown as being rectangular in form but other types of turnbuckle may be utilized.

The plate glass 5 has its opposed edges supported in grooves provided therefor in the glass supporting elements 32 and 33 and the cable passes through the slot 34 in the screws 14. As the wing nut 35 is turnable on the respective screw the cable is tightened and the cup elements 6 and 7 are maintained in pressure engagement with the glass by means of the turnbuckle 13.

By the arrangement of parts as hereinbefore described in respect to Figs. 1 and 4, the cable is maintained in taut condition and provides a rigid support for the cups. The turnbuckles 13 of Fig. 1 or 47 of Fig. 4 may be rotated in one direction to support the cups in pressure contact with the glass and rotated in the opposite direction to release the pressure thereby enabling the apparatus to be removed. In removing the device the peripheral flange of the cups at one or more points in its periphery may be raised from contact with the glass to permit air to flow into the cup or cups depending upon the area of the glass thereby permitting the apparatus to be removed subsequent to releasing the tension on the cable or cables. For this purpose both wing nuts 35 and the turnbuckles 13 are rotated to release the tension on the cable. The plates or brackets 16 and 17 are preferably permanently mounted on the sides 1 and 2 of the window opening.

In the form of the invention shown in Fig. 4 there is a spanner 36 midway between the tensioning screws 37 and 38 on the outer end of which are positioned the cups 39 and 40 respectively. This spanner has a slot 41 in each end thereof to receive the cable strands 42 and 43 and at the base of each of the slots is a slot 44 of less width so that the screws 45 and 46 may be turned to pressure engagement with the cables to thereby hold the spanner 36 in position on the cable.

A turnbuckle 47 is utilized to place the cable under tension longitudinally to thereby maintain the cup elements in pressure contact with the inner surface of the glass whereby the glass is supported from deflection by wind pressure on the exterior thereof. The cups tend to prevent deflection of the glass outwardly when the air pressure on the exterior of the glass is less than the air pressure within the building and thus

serves the same purpose as the structure shown in Fig. 1. By use of the spanner the cable is under greater tension than is the case with the structure shown in Fig. 1.

The cables in Figs. 1 and 4, when in taut condition, hold the cups in pressure contact with the inner surface of the glass and function to resist deflection of the glass inwardly or outwardly depending upon whether the external air pressure is above the pressure within a closed area or below external air pressure. The number of cups utilized depends upon the area of the glass and, in any case, the cables are under tension and provide a rigid support for the glass.

It is believed obvious from the foregoing description in conjunction with the drawings that the apparatus is readily assembled in position in a window opening in the event of an approaching storm and is readily removed as the air pressure returns to normal. It is also believed obvious that the apparatus is comparatively simple and inexpensive in construction, is readily erected when necessary and the cup elements do not mar the glass.

Having thus briefly described my invention, its utility and mode of operation, what I claim and desire to secure by Letters Patent of the United States is—

1. Means for preventing breakage of window glass positioned in a window opening in a building by pressure applied to the exterior of the glass, comprising a pair of rubber cups in spaced relation, a threaded element secured to each cup extending to the exterior thereof, turnbuckles having their one ends threaded on said threaded elements, second threaded elements adjustably mounted upon the opposite ends of said turnbuckles, said second elements each having a longitudinal slot, a cable having the opposite ends thereof connected together providing parallel strands extending through said slots, adjustable means on each of the second threaded elements for placing the cable under tension thereby applying pressure to the cups and supporting the glass, and spaced brackets upon the building upon opposite sides of said window opening through which the opposite ends of said cable extend for supporting the same.

2. Means for preventing breakage of window glass positioned in a window opening in a building by pressure applied to the exterior of the glass, comprising a rubber cup, a threaded element secured to said cup extending to the exterior thereof, a turnbuckle threaded at one end upon said threaded element, a second threaded element adjustably mounted upon the opposite end of said turnbuckle, said second threaded element having a longitudinal slot, a cable having the opposite ends thereof connected together providing parallel strands extending through said slot, adjustable means on said second threaded element for placing the cable under tension thereby applying pressure to said cup and supporting the glass, and spaced brackets upon the building upon the opposite sides of said window through which

the opposite ends of said cable extend for supporting the same.

3. Means for preventing breakage of window glass positioned in a window opening in a building by pressure applied to the exterior of the glass, comprising a rubber cup, a threaded element secured to said cup extending to the exterior thereof, a turnbuckle threaded at one end upon said threaded element, a second threaded element adjustably mounted upon the opposite end of said turnbuckle, said second threaded element having a longitudinal slot, a cable having the opposite ends thereof connected together providing parallel strands extending through said slot, adjustable means on said second threaded element for placing the cable under tension thereby applying pressure to said cup and supporting the glass, spaced brackets upon the building upon opposite sides of said window through which the opposite ends of said cable, extend for supporting the same, and adjustable means interconnecting the ends of said cable.

4. Means for preventing breakage of window glass positioned in a window opening in a building by pressure applied to the exterior of the glass, comprising a pair of rubber cups in spaced relation, a threaded element secured to each cup extending to the exterior thereof, turnbuckles having their one ends threaded on said threaded elements, second threaded elements adjustably mounted upon the opposite ends of said turnbuckles, said second elements each having a longitudinal slot, a cable having the opposite ends thereof connected together providing parallel strands substantially parallel to the window and lying in a plane at right angles to the window and extending through said slots, a pair of adjustable means upon each of said second threaded elements upon the outside of said cable strands for regulating the tension in said cable, said turnbuckles being adjustable to regulate the pressure applied to said cup elements, said cable strands being alternately cooperable respectively with said adjustable means upon each second threaded element for resisting axial movements of said second threaded elements in either direction.
